Hugh R. Weiss, 164 S. Mountain Ave., Montclair, N.J.

Filed Oct. 1, 1963, Ser. No. 76,813

Term of patent 14 years

(Cl. D58—13)

I claim:

The ornamental design for a packaging tray, as shown.
